DRAWBENCH

Max Schunck, Oberursel, near Frankfort-on-the-Main, Germany, assignor to Hermann von Forster, Niederursel, near Frankfort-on-the-Main, Germany

Application August 26, 1937, Serial No. 161,153
In Germany August 28, 1936

8 Claims. (Cl. 205—7)

The invention relates to a drawbench and has for its object a machine of this kind distinguishing itself by simple design and high output. A special object of the invention is to provide a drawbench with a chain running in a horizontal plane round a frame formed in the shape of an I—(double T).

A second object of the invention is to provide a drawbench that automatically throws the finished pieces from the bench on to a transport-truck.

A third object of the invention consists in providing a chain drawbench with a chain alternately movable in opposite directions and capable of also drawing tubes over a mandrel.

Other objects of the invention and the advantages resulting therefrom may be seen from the following description of the invention.

The invention is shown in the drawings accompanying this specification in which

Figure 1 is a side elevational view of the bench according to the invention,

Figure 2 a plan view and

Figure 3 a cross sectional elevation on lines 25 3—3 of Fig. 2.

Figure 4 is a side elevational view partially in section of a special type of the drawbench for drawing tubes over the mandrel.

In the drawings 1 represents the vertical bench-bedding mounted as usual on supports 1. The bedding is formed in the shape of a girder having a middle rib with guides at the top and at the bottom. The drawings show the middle-rib in the shape of a frame of box section. It is advisable to give the latter approximately the breadth of the diameter of the driving chain-wheel. 5 is the chain running on both sides in the plane of the central section of the I-shaped bench-bedding. The guides 6 and 7 are there to guide it. The chain is driven by the chain-wheel 3, while 4 represents a pulley around which the chain can be reversed in its direction of movement, and through which the chain can also be re-stretched, should it have slackened considerably after working a long time. The guides 6 and 7 are formed preferably in the shape of Z-profiles and riveted to the frame of the bench-bedding. They protect the vertically driven chain from falling and sagging. On the side of the drive—that is to say before the chain reaches the pulley 3—there are a set of tension-pulleys mounted on each side. They consist of stationary guide pulleys 8 and 9 and the tension pulleys 11 and 12, each of them being movable in the guides 10 transversely to the chain. Through a

compression-spring 13 the pulleys 11 and 12 push the chain outwards, thus giving it a moderate preliminary tension. If the drawing operation is carried out by the right hand chain, then the tension-pulley 11 is pressed down into the 5 bench by the straightened chain, while the tension pulley 12 moves outwardly and pushed away or restretches the surplus of chain running off the chain-pinion. If the tension-pulleys stretching the chain are properly adjusted there are no 10 chain troubles to be expected on any part of the bench. On the contrary, the chain will always smoothly run on to the chain-wheel. The driving chain-wheel 3 and reversing pulley 4 are mounted on vertical axles 14 and driven by a motor 15 15 with the aid of gearing 16 and a pair of bevel-wheels 17.

The chain moves the two work-gripper carriages 18 and 19, which are provided with the customary drawing-jaws or grippers 20 and 21 20 for seizing the drawing-end of the work-piece. The carriages are guided by means of the pulleys 22 on the middle-rib of the bench-bedding. Thereby they are prevented from sliding off the rib, partly by the upper plate 23 and the lower 25 plate 24, partly by the guides 25, 26, 27 or 28. The work-gripper carriages are firmly coupled to the chain by means of the cams 29 and 30, note Fig. 3, catching into the chain-links. These cams by running off the chain uncouple themselves easily at the end of the bench. In this simple way a clogging of the chain is made impossible. For coupling in again, it is only necessary to push in the carriage by hand.

The middle axis of the drawing-operation, in 35 which the work-grippers or drawing-jaws 20 or 21 lie, can—according to this invention—be adjusted in such a way that it may protrude a little over the outer edge of the lower guides 27 or 28. Consequently the pieces after being drawn can 40 automatically fall into the transport-truck 31 or 32.

At the end of the bench-bedding a cross member 33 is fixed, adjacent to which the die-holders 34 and 35 are fixed which hold the dies and into 45 which the latter are inserted. The disposition of these parts and the mode of fastening them is done in the usual way, I need not go into details. On the side of the dies the necessary control-devices are provided for. By means of them, the 50 motor can be controlled both ways to the effect that the chain can also move in either direction. This control-mechanism being known to the expert, we may pass over its constructional de-

The adjustable reversing pulley 4 gets its tension from the screws 37 and 38 and by inserting the springs 39 or 40, a somewhat elastic tension may be obtained.

5 Figure 4 shows the same construction of bench-bedding, chain and drive shown in Figs. 1-3. To show the details more distinctly, I have only left out the vertical chain where it is guided over the wheels 3 and 4 and the middle-portion of the 10 construction.

In the drawing 40 represents the mandrel, which is inserted into the tube 41. The mandrel is put into a gripping device, consisting of a split inserted nozzle 42 adjustable by means of a hand-wheel 43. In its closed position the gripping mechanism clasps the mandrel-head 44 in a notch and holds it fast during the drawing operation. When it is opened the bloom- or lump-tube 41 can be put through the opening over the mandrel and 15 the die 45 can be put on the latter, while, the drawing operation being terminated, the finished tube can be slipped off. On the other side the mandrel is bedded in the gripping device 46, which is fixed on the transverse member 47. The mandrel is supported by the pulleys 48, fixed to the 20 rocking-lever 49. According to this method of tube drawing, the gripper-carriage 50 is of a different construction. Instead of closed jaws the carriages are provided with an opening 51, through which the central-axis of the mandrel passes. This opening is wide enough to let the die through. The carriages are provided with devices 52 which hold the die fast during the drawing-operation and with flaps 53 for slipping the 25 tube from the mandrel during the reverse movement of the carriage. The connection of the carriage with the chain is identical with the one in use in drawing through dies as described before. The flaps 52, which are fitted to hold the dies 30 fast, or the slipping off device 53, are disposed in such a way as to act upon the mandrel while they are in operative position, but to offer passage by snapping open whilst they are not in action. For that purpose they are movably mounted on bolts 54 and 55 on the carriages.

40 The rollers 56 or 57, equally mounted in the carriage, immediately loosen the tubes on the mandrel as soon as the drawing operation is finished. To give free passage, these rollers can be 35 opened by lifting the flap pivoted supporting arms 58 or 59.

The bench (for instance while drawing bars through the dies) works as follows according to the invention.

Seen by the operator the transport-truck 45 loaded with draw-ware is as usual standing on the service side of the bench. On the left and right sides of the bench are the transport-trucks waiting for the finished articles. The end of a work-piece, for instance of a bar, being put (on the left 50 side of the bench) through the die into the jaws of the gripper-carriage, the latter is coupled in and made to run forward, that is to say to "draw". During the forward-movement of this gripper-carriage and the corresponding backward-movement of the gripper-carriage on the 55 right side of the bench, the right side of the bench is already charged or fed with a new work-piece. The work-piece on the left side having passed the die, falls automatically into the transport-truck without any additional manipulation or help given by the operator. At this moment, whilst the gripping carriage is stationary on the right side of the bench at the working stand, the driving motor is reversed and the gripping carriage of the right side of the bench is coupled 60

in. Thus a drawing operation is started on this side, while the gripper carriage of the left side is running back. The drawing-operation being finished on the right side and the drawn work-piece having fallen in the transport-truck, the motor or the direction of the chain-drive is reversed, whereupon (the left side gripper-carriage being coupled in again) another drawing operation is performed here, while the right-side gripper carriage runs back empty. As shown the drawing-operation is performed now by the right and now by the left chain portion, for which purpose only the direction of the chain-drive must be reversed every time. The operator of the bench may remain standing at the head of the bench all the 15 time only coupling and charging or feeding the sides of the bench with draw-ware. It is easily understood that by this mode of working the output is considerably increased, the staff reduced and the production cost considerably lessened. 20

This working method offers many advantages. On the one hand the bench works as a double bench with only one chain running, whereby the costs of the plant are reduced. On the other hand there is less light running and considerably less staff needed, as the throwing out of the finished work-pieces is automatically performed. 25

While drawing tubes over a mandrel the working method is as follows:

First insert the mandrel, then draw a bloom- 30 or lump-tube over it through the opened gripping device, fix the mandrel firmly and move the drawing-device over the fixed mandrel by means of the carriage, which is provided with catches. A step or offset 60 in the mandrel prevents in the 35 usual way the tube from being taken along. While on one side the drawing and simultaneously the loosening is going on, the stripping off takes place on the other side not shown in Fig. 4. Here also the bench works as a double-bench offering the advantage of increased output and reduced 40 staff.

A special advantage is offered by the drawing of tubes over the mandrel on the drawbench according to the invention, if more than the usual one drawing-operation, is to be performed on the 45 same mandrel over the tube without exchanging the mandrel. If several drawings are to be made successively on the same mandrel, then at the beginning of the drawing operation instead of one die, several dies of gradually diminishing diameter are put on the mandrel. The first die placed on the mandrel is of course the largest, and is connected to the carriage. The carriage is then run the length of the mandrel and one draw is thus made on the tube. Before the carriage is 55 returned, the first die is disconnected, so that the carriage alone returns to the starting point. The second die is then connected to the carriage and a second draw is made. Successive drawings are likewise made until the tube has reached the 60 desired size. One time the right carriage is drawing, while the left is running backwards and the other time the left is drawing while the right is running backwards. Because the reverse-movement on one side coincides with the forward-movement on the other, the light running-periods and thereby the production-costs are considerably reduced. 65

I claim:

1. A drawbench comprising a bench-bedding 70 having vertical sides, a chain extending adjacent said sides, at least one gripping carriage, means for coupling said carriage to said chain, means for mounting and guiding said carriage along at least one of said vertical sides to carry 75

a work piece in a plane outside of and parallel to said sides, and means driving said chain alternately in opposite directions.

2. A drawbench comprising a bench-bedding-frame in the form of an I, a chain means for mounting and guiding said chain substantially midway of and on opposite sides of said I, at least one gripping-carriage, means to couple the chain on to said gripping carriage, a driving chain-wheel 10 with vertical driving axle, a pulley with vertical axle for the chain, and means for driving the chain in both directions.

3. A drawbench comprising a bench-bedding consisting of a vertical middle-rib, guides 15 mounted on both sides of said middle-rib, a continuous chain supported by these guides on both sides of the middle-rib, two gripping carriages moved by means of the chain on both sides of said middle-rib, devices to couple the gripping 20 carriages on to the chain, a drive chain-wheel with vertical driving axle for the chain and means for driving the chain in both directions.

4. A drawbench comprising a bench-bedding having a vertical middle-rib and plates protruding on both sides over the middle-rib at the 25 top and at the bottom, at least one die mounted on one end of the said bench bedding, a continuous chain supported about both sides of said middle-rib, at least one gripping carriage moved 30 by the chain, means to grip the articles to be drawn, said means being mounted on said gripping-carriage in such a way that the projection of the connecting lines from these means to the dies falls outside the plates, that are fastened 35 underneath to the said middle-rib, devices to couple the gripping-carriages on the chain, a driving chain-wheel with vertical driving axle, a reversing-pulley with vertical axle for the chain and means for driving the chain in both directions.

5. A drawbench comprising a bench-bedding-frame in the shape of a sole plate frame of box section, a chain mounted vertically and substantially midway of both sides of said frame, gripping-carriages running on the side walls of said frame, means to couple said gripping-carriages on to the chain, a drive chain-wheel, a pulley, said driving chain-wheel and said pulley having a diameter corresponding approximately to the breadth of said frame, and means for driving the 10 chain in both directions.

6. A drawbench comprising a bench-bedding-frame in the shape of a sole plate frame of box section, a continuous chain supported about both sides of said frame, gripping carriages mounted 15 for movement by said chain, means for driving this chain in alternate directions, elastic chain stretching devices for restretching the non-drawing portion of the chain by means of deviation, but allowing the drawing portion to run through 20 in a straight line from said driving means to a gripping carriage.

7. A drawbench according to claim 6 comprising sets of tension- and guide-pulleys placed near the driving chain-wheel before the on-run and 25 the off-run of the chain.

8. A drawbench comprising a bench-bedding-frame in the shape of a sole plate frame of box section, a chain supported about both sides of said frame in a horizontal plane, at least one 30 gripping carriage, means including said chain for moving this gripping carriage along the sides of said frame, means for fastening a mandrel at the sides of the frame of the bench-bedding and means for drawing tubes and for loosening the 35 tubes from the mandrel which are mounted on the gripping carriage.
